UNITED STATES PATENT OFFICE.

CHARLES W. NICHOLS, OF PARIS, TEXAS, ASSIGNOR OF ONE-HALF TO W. E. HOGUE
MANUFACTURING COMPANY, OF PARIS, TEXAS, A CORPORATION OF TEXAS.

ACETYLENE GENERATOR.

Application filed July 15, 1921. Serial No. 484,898.

To all whom it may concern:

Be it known that I, CHARLES W. NICHOLS, a citizen of the United States, residing at Paris, in the county of Lamar and State of 5 Texas, have invented a new and useful Acetylene Generator, of which the following is a specification.

This invention relates to gas generators and is more particularly directed to an 10 automatically controlled acetylene generator.

Heretofore, generators have been constructed in which the feeding means for the calcium carbide is operated by a motor located exteriorly of an air-tight drum in 15 which the gas is generated. This necessitates packing the journals of the shaft very firmly where they pass through the drum to prevent the escape of gas and therefore greater power is required to operate the 20 shaft.

Or, as an alternative, the feeding means is operated by the pressure of the gas generated within the drum, and this pressure must be low in order to effectively produce 25 a steady flow of gas; nevertheless, low pressure in the gas drum is undesirable since it considerably limits the distance through which the gas may be distributed.

It is an object of my invention to provide 30 as a feeding means for the carbide a wheel which is operated by the descent of the carbide, and to control said feeding means by a mechanism which is positioned within a chamber outside the drum. The generated 35 gas which is under relatively high pressure within the drum is adapted to automatically stop the operation of the feeding mechanism when a predetermined limit is reached, while a governor is employed to control the 40 speed of the feeding wheel.

The invention will be best understood from a consideration of the following detailed description taken in connection with the accompanying drawing forming part of 45 this specification, with the understanding, however, that the invention is not confined to any strict conformity with the showing in the drawing, but may be changed and modified so long as such changes and modifications mark no material departure from the salient features of the invention as expressed in the appended claims.

In the drawings:

Fig. 1 is a vertical elevation of a drum 55 and the operating mechanism.

Fig. 2 is a fragmentary view in detail of the feeding device.

Fig. 3 is a horizontal section of the generator taken along the line 3—3 of Fig. 1.

Fig. 4 is a fragmentary view in detail of 60 the governing and controlling means for the feeding device.

Fig. 5 is a sectional view through the 65 governor and the chamber in which it is operated.

In the drawing, 1 designates a container or drum which is provided with a base 2 concaved inwardly, and a top 3 to which is secured a depending hopper 4 adapted to carry a certain quantity of calcium carbide. 70 The central portion of the top 3 is perforated, and concentrically with the perforation is secured an externally threaded nipple 5 upon which is screwed an internally threaded cap 6. A washer 7 is located between the outer periphery of the nipple 5 and the cap 6 to prevent the escape of gas from the hopper and drum. The nipple 5 provides a means for filling the hopper 4 75 with calcium carbide.

A feeding wheel 8 provided with a plurality of spaced buckets 9 upon its exterior surface, has its vertical diameter placed to one side of the lower opening or mouth 10 of the hopper 4, in order that the carbide in 80 the hopper will drop upon the buckets 9 as they pass beyond the upper dead center of the wheel and cause the wheel to be operated thereby. A flanged plate 11, secured to the 85 sides of the drum and to the hopper 4, surrounds the opening 10, and is adapted to direct gas away from the mouth or opening 10 and support the mouth 10 centrally of the drum. One end of a shaft 12 is mounted 90 in bearings 13 secured to one side of the drum 1, the other end of the shaft being mounted in a diametrically oppositely disposed bearing 14 located upon the inner wall 19 of a chamber 15. This chamber is made 95 rectangular in form with sides, top and bottom 17. To receive the chamber, a portion 100 of the drum is pressed inwardly forming a supporting shoulder 16 and a wall 19 which serves as the back for the chamber, an opening 20 cut in the drum above the 105 back wall providing communication between the drum and said chamber. The chamber is secured to the shoulder 16, and to the top of the drum where the latter is cut as indicated at 20, and a cover plate 18 is se-

110

cured to the flanged portion 17^a of the sides, top and bottom of the chamber by numerous screws or bolts. A washer 18^a is interposed between the flanges and the cover plate to prevent the escape of gas generated in the drum 1.

It is to be understood therefore that the drum 1, in the upper portion of which the hopper 4 is supported, and the shoulder 15 secured to the side of the drum and in communication therewith through the opening 20, together constitute a hermetically sealed tank within which the gas is produced.

15 In order to provide a uniform speed for the feeding wheel 8, a governor is employed in the chamber 15 and connected with the shaft 12.

An end 21 of the shaft 12 extends beyond 20 the bearing 14 and into the chamber 15, upon which is mounted a perforated substantially cylindrical governor drum 22 adapted to be partially immersed in a liquid which fills the chamber 15 at least half 25 full, as shown by the dotted lines in Figs. 1 and 5.

The drum governor 22 is divided into four chambers designated by the letters *a*, *b*, *c*, *d*, by means of the partitions 23 which are at 30 right angles to each other. The outer sides of each chamber, which form the ends of the drum 22, are provided with a plurality of perforations or openings, designated by the numeral 24, 35 are formed in each chamber of the drum 32 and close to the axis of rotation of the drum. The other perforations, designated by the numerals 25 and 26, are located near the periphery of the drum close to the partitions 40 23, or in the outer opposite corners of each chamber *a*, *b*, *c*, *d*. As will be explained later, the governor drum being rotated in the water or some other liquid, will permit the liquid to enter certain of the perforations or ports, but as the chambers are elevated when the shaft is rotated, liquid will 45 escape through certain of the perforations and control the speed of rotation of the shaft, which in turn will control the speed 50 of rotation of the wheel 8.

There may be times when it is necessary, in view of the liquid collected in the drum 22 and the calcium carbide filling up a 55 space between two of the buckets 9 which has checked the flow of the carbide from the hopper 4, to manually start the rotation of the shaft 12 and wheel 8. This may be done by providing a cranking means which is adapted to engage at times a member on 60 the shaft 12, and to cause rotation of the shaft when the cranking means is operated. Therefore, a rotatable and slidable shaft 29, provided with a crank 30 and an operating handle 31, is journaled in a boss 32 formed centrally on the cover plate 18. The cover

has a centrally located perforation through which is inserted the shaft 29. This crank 30 on the inner end of the shaft 29 is adapted to engage the spaces between the web of a toothed wheel 33 as the handle 31 is 70 pushed inwardly towards the cover 18. The packing 34 and internally threaded nut 35 are screwed down upon the boss 32 to prevent the escape of gas from the chamber 15 around the shaft 29. 75

The toothed wheel 33 is rigidly mounted on the extended end 21 of the shaft 12, and as the handle 31 is turned when the crank 30 of the shaft 29 engages the web of the wheel 33, it will cause the shaft 12 and the 80 wheel 8 to rotate.

A manually operated dog or stop 36 projects into the path of the toothed wheel 33 and is adapted to engage a tooth thereof at certain times to prevent rotation of the toothed wheel and likewise the shaft 12 and the feed wheel 8. This stop 36 is secured upon a shaft 37 which passes through the cover 18 and centrally through a boss 38 integrally formed on the cover, and is provided with packing and a nut 39 similar to the packing and nut employed for preventing the escape of gas from the boss 32. A handle 40 upon the outer end of the shaft 37 is adapted to operate the shaft and likewise the stop 36. 95

In order to automatically control the operation of the wheel 8, a device is employed which is controlled by the pressure of the gas to prevent rotation of the toothed wheel 33 and also the feed wheel 8. This device comprises a casing 41 which is secured in any approved manner to the top 17 of the chamber 15, and communicates with the chamber 15 by means of a passageway 42, in which is reciprocated a rod 43 mounted at its lower end in a bearing 44 secured to the side of the chamber 15, and at its upper end rigidly secured centrally of a diaphragm 45. The diaphragm, at its periphery, is securely fixed to the upper edge of the casing 41 by means of an internally threaded cap 46 engaging the external threads upon the casing 41. The rod 43 is permitted to project outwardly through an opening centrally formed in the cap 46. 110

To the extreme lower end of the rod 42 is secured a stop 47 having a toe 48 which is adapted to be moved into the path of the rotating toothed wheel 33, and to be engaged between a pair of the teeth on the wheel when the diaphragm 45 is forced outwardly by reason of the pressure of the gas in the chamber 15 and the drum 1. As soon as the pressure of the gas falls, by reason of the same being carried off through the pipe 48^a to the flash back tank, the diaphragm will automatically return and the toe 48 of the stop 47 will be moved downwardly and out of engagement with the 125 130

teeth of the wheel 33, when the carbide which has collected in a heap between the buckets 9 of the wheel 8 and stopped the flow of the carbide from the mouth 10 of the hopper 4, will, by the force of gravity, cause the same to tend to descend, and thereby rotate the wheel 8. The carbide being projected into the water which partially fills the drum 1 will cause the generation of a new supply of gas and increased pressure. When the pressure of the gas has become sufficiently great to operate the diaphragm 45, the clutch 47 will again be caused to stop the toothed wheel 33.

15 An inlet pipe 49, provided with a screw-threaded stopper 50 engaging the internal threads of the pipe, is adapted to provide a means for re-filling the drum 1 with water. A similar pipe 51 provided with a screw-threaded stopper 52, provides a means for supplying the chamber 15 with the proper amount of liquid to control the rotation of the drum 22. A valved pipe 53 connected with the interior of the drum 1 is adapted to 25 provide an outlet for the water and calcium deposits which forms a sediment on the bottom 2 of the drum 1.

The operation of my device is as follows:—

30 The stopper 50 is removed from the pipe 49 and the drum is partially filled with water, until the water appears to stand in the pipe 49, when the stopper 50 may be replaced. The stopper 52 may also be removed from the water pipe 51 and the chamber 15 partially filled with liquid until the same appears at the top of the pipe 51, when the plug 52 may be returned to its position. The brake 36 is thrown into engagement 35 with the toothed wheel 33 by means of the handle 40 to prevent rotation of the toothed wheel and the feeding wheel 8. The stopper 6 and the washer 7 are then removed from the boss 5 secured upon the top 3 of the drum 1, and the calcium carbide is poured in through the opening in the boss until the hopper 4 is filled, when the washer 7 and the stopper 6 may be replaced in position to hermetically seal the drum. Some 40 of the carbide pouring from the mouth of the hopper will be deposited on the wheel 8 between a pair of buckets 9, and will collect there in a pile sufficiently high to prevent any further flow of the carbide from 45 the mouth.

The shaft 29 is moved inwardly into the chamber 15, by means of the handle 31, in order that the crank 30 will enter in the space between the webs of the toothed wheel 33. The handle 40 is rotated to move the brake 36 from engagement with the toothed wheel 33, and the handle 31 is then rotated, causing the toothed wheel to rotate the shaft 12 and the feeding wheel 8, when the carbide 50 which has been deposited between a pair of

the buckets 9 of the wheel 8 and choked the mouth 10 of the hopper, is precipitated into the water, permitting the carbide to flow freely onto the wheel and causing said wheel to rotate.

70 Since the feeding of the carbide on the wheel 8 is only restricted by the area of the opening 10 of the hopper 4, a governor in the chamber 15, comprising the drum 22, cooperating with the liquid in the chamber, is 75 employed to control the speed of rotation of the feeding wheel 8.

Referring to Figs. 4 and 5, the operation of the governor is as follows:—The lower half of the governor drum 22 is submerged 80 in liquid and because of the perforations 26, liquid will be admitted to the two lower chambers *c* and *d* of the drum, air being driven out through perforations 24 and 25. As chamber *c* is elevated and the perforations 24 rise above the plane passing through the horizontal axis of the drum, liquid will pour from the openings 24, and at the same time enter the submerged perforations 26 of chamber *b*, air entering the perforations 25 and 26 of chamber *a* and being expelled through perforations 25 in chamber *b*. As 85 the rotation of the drum is continued in the direction shown by the arrow in Fig. 5, the chamber *d* will also be passing towards the direction taken by the chamber *c*, and when the perforation 24 of that chamber has passed above the horizontal plane just described, liquid will begin to run out of the perforations 24, as air enters openings 25 and 26. Liquid from the chamber *c* will have had time to drain at about the time chamber *a* is submerged. Each chamber in 90 its turn will be immersed and then removed from contact with the liquid so that the perforations 26 will always operate to permit liquid to flow into a chamber when the chamber is completely immersed, while the perforations 24 will permit the water to drain when the chamber is in elevated position 95 and out of contact with the liquid. Air is principally expelled through perforations 25, but sometimes they permit liquid to flow through them when all the liquid does not escape through perforations 24. It will be seen that the constant flow of liquid to and 100 from the chambers alternately produces a well balanced structure, and keeps the feeding wheel from operating too fast.

110 In my apparatus, the feeding of the carbide is controlled and automatically stopped by the pressure of gas. The main shaft 12 is only operated about fifteen times to one hundred pounds of carbide. If desired, the controlling and governing means for the shaft 12 may be duplicated at each end of 115 said shaft.

What is claimed is:—

1. In an acetylene generator, a tank for 120 containing gas-producing elements, a shaft

- rotatably mounted entirely within the tank, means for progressively feeding one of the gas-producing elements to the other element, said feeding means being operable by the 5 weight of the progressively fed element to cause rotation of the shaft to control the flow of the progressively fed element, and means on the shaft inside the tank for controlling the speed of the shaft.
- 10 2. In an acetylene generator, a tank for containing the gas producing elements, a shaft rotatably mounted inside the tank, a hopper within the tank located above the shaft for containing a supply of one of the 15 gas producing elements, means for progressively receiving quantities of said element from said hopper, adapted to be actuated by the weight of said quantities to rotate the shaft and to deliver them to the 20 other element, and a fluid operated governor secured to the shaft for retarding the rotation of the same.
- 25 3. In an acetylene generator, a tank for containing the gas producing elements, a shaft rotatably mounted entirely within the tank, a wheel secured to the shaft and having a circumferential series of buckets, a hopper within the tank having an outlet directly above the path of said buckets at 30 one side of the shaft, whereby the weight of the material discharged from the hopper causes the rotation of the shaft, and means secured to the shaft for retarding its rotation.
- 35 4. In an acetylene generator, a tank adapted to contain gas-producing elements, a shaft rotatably mounted entirely within the tank, means on the shaft for progressively feeding one of the gas-producing elements to the 40 other element, said feeding means being operable by gravity to cause rotation of the shaft to control the flow of the progressively fed element, a governor inside the tank for controlling the speed of rotation of the shaft, 45 and means automatically actuated when the gas generated in the tank reaches a predetermined pressure to positively stop the rotation of the shaft.
- 50 5. In an acetylene generator, a drum adapted to be partially filled with water, a shaft rotatably mounted within the drum, a wheel rigidly mounted on the shaft, a hopper arranged to feed a granular gas-producing substance to operate the wheel by 55 gravity and thereby to progressively feed said substance to the water, a chamber in communication with the drum above the operative level of the water, the shaft being journaled at one end in the drum and at its 60 other end in the chamber, and a governor on said shaft within the chamber for controlling the speed of rotation of said shaft.
- 65 6. In an acetylene generator, a drum adapted to be partially filled with water, a bucket wheel rotatably mounted within the drum, a hopper arranged to feed a granular gas-producing substance to operate the wheel by gravity and thereby to progressively feed said substance to the water, a chamber in communication with the drum above the operative level of the water, the shaft being journaled at one end in the drum and at its other end in the chamber, and a governor on said shaft within the chamber for controlling the speed of rotation of said shaft.
- 70 7. In an acetylene generator, a tank adapted to contain gas-producing elements, means for progressively feeding one of said gas-producing elements to the other element, and a governor adapted to control the feeding of said element comprising a perforated drum partially submerged in water and adapted to be operated by the feeding means.
- 75 8. In an acetylene generator, a tank adapted to contain water, a hopper within the tank for containing calcium carbide, a rotatable element extending into the path of carbide discharged by the hopper and rotatable by the weight of the carbide, and means secured in fixed relation to the wheel and operable when partially submerged in water for continuously retarding the speed of rotation of said element.
- 80 9. In an acetylene generator, a hermetically sealed tank adapted to contain water, a hopper within said tank for containing calcium carbide, means beneath the hopper for feeding the carbide into the water including an element rotatable by the weight of the carbide as it falls from the hopper, means within the tank for continuously retarding the speed of said rotatable element, and means also within the tank for positively stopping the rotation of said element when the gas within the tank reaches a predetermined pressure.
- 85 10. In an acetylene generator, a tank for containing gas-producing elements, a shaft rotatably mounted entirely within the tank, means on the shaft for progressively feeding one of the gas-producing elements to the other element, said means being operable by gravity to cause rotation of the shaft to control the flow of the progressively fed element, means on the shaft located in a chamber separate from the feeding means for continuously retarding the speed of rotation of the shaft, and means for automatically stopping the rotation of the shaft when the gas within the tank reaches a predetermined pressure.
- 90 11. In an acetylene generator, a tank adapted to contain gas-producing elements, a rotatably mounted shaft, a bucket wheel fixed on the shaft, means for feeding one of the gas-producing elements to said wheel and thereby rotating it, a toothed wheel fixed on said shaft, a manually operated stop adapted to cooperate with the toothed wheel for preventing rotation of the shaft and bucket wheel, a second stop adapted
- 95 100 105 110 115 120 125 130

- to cooperate with the toothed wheel to prevent rotation of the shaft, said second stop being automatically operated by a predetermined pressure of gas within the tank, 5 a manually-operated means normally out of engagement with the toothed wheel and adapted to be moved into engagement therewith and rotated for starting the rotation of the shaft.
- 10 12. In an acetylene generator, a drum adapted to contain gas-producing elements, a chamber having its upper portion in direct communication with the upper portion of the drum, a rotatably mounted shaft having one end projecting into the chamber, a bucket wheel fixed on the shaft, means for feeding one of the gas-producing elements to said wheel and thereby rotating it, a toothed wheel fixed on the end of the shaft 15 within the chamber, a stop adapted to cooperate with the toothed wheel for preventing rotation of the shaft and bucket wheel, and a governor secured to the end of the shaft in the chamber for controlling 20 the speed of rotation of said shaft.
13. In an acetylene generator, a hermetically sealed tank adapted to contain gas-producing elements, a shaft rotatably mounted within the tank, a bucket wheel secured to the shaft, means for feeding one of the gas-producing elements to said wheel and thereby rotating it, a chamber within the tank into which the shaft projects, a toothed wheel secured to the shaft within 25 the chamber, a casing in communication with the chamber and provided with a diaphragm, and provided with a stop adapted to be projected into engagement with the toothed wheel to prevent the rotation of 30 the shaft when the pressure of the gas forces the diaphragm outwardly.
14. In an acetylene generator, a drum adapted to contain gas producing elements, means for progressively feeding one of said 35 gas producing elements to the other to form a gas, a chamber in communication with the drum, said chamber being partially filled with liquid, and a governor adapted to control the feeding of said element comprising a drum partitioned off into a plurality of chambers, the chambers being provided with openings near their peripheries for the admission of liquid when each chamber is alternately submerged in the liquid, and other openings located near the axis of 40 rotation of the drum adapted to permit the liquid to escape as the chambers are elevated from the liquid, and other perforations in the chamber adapted to admit air and at another time permit air to be expelled through them.
15. In an acetylene generator, a drum, a hopper for containing carbide, a feeding wheel in communication with the hopper, a shaft on which said wheel is mounted, a closed chamber provided on the exterior of the drum but having communication therewith, a water-controlled governor contained within the chamber and mounted on the end of said shaft and operable to 45 continuously reduce the speed of rotation of the shaft, and means for supplying the chamber with water in which the governor may operate.
16. In an acetylene generator, a drum 50 adapted to contain gas-producing elements, a chamber in communication with the drum, a rotatably mounted shaft having one end projecting into the chamber, a bucket wheel fixed on the shaft means for feeding one 55 of the gas-producing elements to said wheel and thereby rotating it, a toothed wheel fixed on the end of the shaft projecting in the chamber, and a rotatably and slidably mounted shaft provided with a crank at 60 its inner end and a handle at its outer end for engaging the toothed wheel for manually rotating the latter and the shaft on which it is mounted.
- In testimony, that I claim the foregoing 65 as my own, I have hereto affixed my signature.

CHAS. W. NICHOLS.
